(57) **CLAIM**

The ornamental design for an electronic device cover, as shown and described.

DESCRIPTION

FIG. 1 is a top, front perspective view of an electronic device cover showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The evenly spaced broken lines in the figures illustrate portions of the design that form no part of the claimed design. The dash-dot broken lines in the figures represent the boundaries of the claimed design and form no part of the claimed design.

The shading is provided merely to represent contours of the design and does not connote the character of the surfaces such as any specific texture, material, gloss, translucence, transparency, surface treatment, or surface decoration.
